UNITED STATES PATENT OFFICE

CLAES W. BOMAN, OF NEW YORK, N. Y., ASSIGNOR TO EAGLE PENCIL COMPANY, OF NEW YORK, N. Y.

DESIGN FOR AN AUTOMATIC LEAD AND CRAYON HOLDER.

No. 39,561.

Specification for Design.

Patented Sept. 22, 1908.

Application filed July 17, 1908. Serial No. 444,148. Term of patent 3½ years.

To all whom it may concern:

Be it known that I, CLAES W. BOMAN, a citizen of the United States, residing at New York, borough of Brooklyn, county of Kings, State of New York, have invented a new, original, and ornamental Design for Automatic Lead and Crayon Holders, of which the following is a specification, reference being had to the accompanying drawing, which is a perspective view, full size, of the holder.

The case A of the holder is noticeably thick in proportion to its length and is smooth and cylindrical throughout its length with the exception of the short tip B which is conical. On the body A some little distance back of where the tip merges into the body

there is an annular bead a. The case of the holder terminates in a cylindrical cap C of less diameter than the body A, which latter, at the point where it joins the cap, has a rounded annular shoulder b. The head of the cap is also slightly rounded. The lead holding jaws D protrude slightly beyond, and continue on the conical lines of, the tip.

I claim—

The ornamental design for an automatic lead and crayon holder, as shown and described.

CLAES W. BOMAN.
